UNITED STATES PATENT OFFICE.

HUGO MÜLLER AND WILLIAM A. JACKSON, OF OAKLAND, CALIFORNIA.

INTERCHANGEABLE FORK-CROWN.

SPECIFICATION forming part of Letters Patent No. 714,936, dated December 2, 1902.

Application filed April 10, 1902. Serial No. 102,180. (No model.)

To all whom it may concern:

Be it known that we, HUGO MÜLLER and WILLIAM A. JACKSON, citizens of the United States, residing at Oakland, county of Alameda, and State of California, have invented an Improvement in Interchangeable Fork-Crowns; and we hereby declare the following to be a full, clear, and exact description of the same.

10 Our invention relates to improvements in bicycle fork-crowns. Its primary object is to provide a crown to which the forks may be secured otherwise than by the ordinary method of brazing, which necessarily weakens a vital 15 part of the machine.

A further object is to provide a spring-fork of extreme simplicity, strength, and durability particularly adapted to our crown.

It consists of a crown integral with the 20 steering-post and having segmental flanges at its ends, fork sides adapted to fit within and be embraced by said flanges, and means for locking the crown and fork sides together.

Having reference to the accompanying 25 drawings, Figure 1 is a perspective view of our invention. Fig. 2 is a front view and part section. Fig. 3 is a view of a spring-fork. Fig. 4 is a view of a cap. Fig. 5 is a sectional view of the upper part of a solid fork. Fig. 30 6 is a sectional view of the upper part of a solid fork bolted vertically.

A represents the steering-post of a bicycle. The crown 2 is integral with the post. Its 35 ends are provided with segmental flanges 3, which extend outwardly in the direction of the axis of the crown to form a socket or recess 4 open toward the lower end of the post. The sides of the flanges are approximately parallel and are a trifle extended below the 40 lower side of the crown-piece, so as to give a sufficient bearing for the fork sides, which are adapted to fit into the sockets 4. The fork sides may be of either the rigid or the spring type, preferably the latter, as the 45 crown has been designed particularly for this style. The fork sides are each made of a single piece of spring-steel bent upon itself to form a main spring portion 5 and a reinforcing-leaf 6, as in Fig. 3. The bent portion 7 of the spring is of a shape and size just to fit snug within the walls of the sockets 4. The 50 lower end of the portion 5 may be curved

slightly, and slots 8 are adapted to receive the axle-bolt of the front wheel of the bicycle. The leaf portion 6 engages the portion 5 intermediate of the ends of the latter to give the proper resiliency and added strength required. In the bottom of each socket 4 is a projecting boss or lug 9, which engages the adjacent sides of the spring members 5 and 6. The space between the lug and either side of its corresponding flange 3 is just sufficient to admit the fork side, so that the latter is firmly supported in the socket and prevented from turning.

65 The crown has a perforation 10 extending through it lengthwise. A perforated cap 11 fits on over the outer end of each of the flanges to give finish to the wheel and prevent lateral displacement of the forks, and the parts 70 are locked together by means of a bolt 12, passing through the eyes 13 of the fork sides. The caps have each a peripheral flange 19, overlapping the flange 3, and a projection 20, fitting between the spring members 5 and 6 75 and coöperating with the lugs 9 to lock the fork sides more firmly. There may be a bolt for each cap screwing into a threaded portion at either end of the perforation 10 in the crown, in which case the outer end of the 80 bolt may have a polygonal walled socket 13^a, adapted to receive a wrench, or a single bolt may be passed entirely through the crown and both caps.

The crown-sockets are adapted to receive 85 a rigid fork of the construction shown in Fig. 5.

The fork 5' is made with a solid enlarged head portion 7' of a shape and size to fit the sockets and provided with a recess 14 to accommodate the lugs 9. It has an eye 13' coincident with the perforation in the cap and that in the crown through which the locking screw or bolt is inserted.

90 In Fig. 6 is shown another means for locking the fork sides in the crown-sockets. In this case the fork side is made with a drawn-bolt portion 16 at the bend or upper end which is turned down and threaded and is adapted to project through a hole 17 in the 100 wall of the socket when the head is fitted in the latter. The parts are locked together by means of a nut 18.

With this invention applied to a bicycle it

- permits the manufacturer to use the same crown with any weight or style of spring required. In case a fork side becomes broken it can be quickly replaced, thereby obviating the necessity of discarding the entire fork. By rendering the parts thus interchangeable it effects a saving in many cases and admits of a wheel being fitted to the taste, weight, or other requirements of the rider.
- 10 Having thus described our invention, what we claim, and desire to secure by Letters Patent, is—
1. The combination of a steering-post, a crown-piece integral therewith and having 15 sockets opening outwardly in a horizontal plane, and fork sides detachably secured to said crown.
  2. The combination of a steering-post, a fork-crown, having sockets with open ends 20 facing in opposite directions, fork sides fitting said sockets and means by which said sides are detachably secured in said crown.
  3. The combination in an interchangeable fork-crown, of a steering-post, a crown-piece 25 having flanges at its ends and having sockets open on two sides, fork sides, said flanges adapted to embrace said fork sides and means by which said fork sides are detachably secured to the crown-piece.
  - 30 4. The combination of a steering-post, a crown-piece in which are sockets open on two sides, fork sides fitting said sockets, said fork sides each consisting of a single piece of steel

bent upon itself, and means by which said sides are detachably secured to said crown- 35 piece.

5. The combination in an interchangeable fork-crown, of a steering-post, a crown-piece having outwardly-extending segmental flanges at its ends, spring fork sides each consisting of a single piece of steel bent upon itself, the bent portion of said fork sides fitting within and adapted to be embraced by said flanges, a cap fitting over the end of said flanges and a bolt by which the parts are held 45 together.

6. The combination in an interchangeable fork-crown, of a steering-post, a longitudinally-perforated crown-piece integral therewith, said crown-piece having sockets open 50 at one side and the bottom, fork sides adapted to be inserted into said sockets, caps by which the open side of the sockets is closed and the fork sides prevented from lateral displacement, projections or lugs engaging the 55 fork sides to prevent their turning, and a bolt adapted to be embraced by the fork sides and fit the perforation of the crown-piece whereby the parts are locked together.

In witness whereof we have hereunto set 60 our hands.

HUGO MÜLLER.

WILLIAM A. JACKSON.
